[57] CLAIM

The ornamental design for a dispenser for cups and packaged materials, as shown and described.

DESCRIPTION

FIG. 1 is a front elevational view of a dispenser for cups and packaged materials showing our new design;

FIG. 2 is a side elevational view thereof, the side opposite being substantially a mirror image;

FIG. 3 is a top plan view thereof;

FIG. 4 is a rear elevational view thereof; and

FIG. 5 is a bottom plan view.

FIG. 1.

FIG. 2

FIG. 3.

FIG. 4.

FIG. 5.
